Patented July 27, 1915.

UNITED STATES PATENT OFFICE.

WALTER C. B. FARRAR, OF HUNTINGTON, INDIANA.

DEVICE FOR SHARPENING SHEARS.

1,148,303.

Specification of Letters Patent. Patented July 27, 1915.

Application filed November 23, 1914. Serial No. 873,607.

To all whom it may concern:

Be it known that I, WALTER C. B. FARRAR, a citizen of the United States of America, residing at Huntington, in the county of Huntington and State of Indiana, have invented certain new and useful Improvements in Devices for Sharpening Shears, of which the following is a specification, reference being had therein to the accompanying drawing.

This invention relates to a device for sharpening shears and has for its principal object the production of a simple and efficient means for supporting a pair of shears at a desired angle so as to allow the same to be easily engaged by a reciprocating stone for imparting the correct bevel to the shears as the same are being sharpened.

Another object of this invention is the production of a device for sharpening shears which is provided with a foldable guide post which carries a reciprocating rod to which the stone is supported whereby the stone may easily reciprocate for sharpening a pair of shears carried by the device.

Another object of this invention is the production of an adjustable device for holding the shears in a set position whereby the shears may be easily sharpened while the same are held in a position to allow the correct bevel to be imparted thereto.

Still another object of this invention is the production of a device for sharpening shears in which the portions are adapted to be supported for accommodating different sized shears, these portions being capable of being folded to assume a compact position when the device is not in use.

With these and other objects in view this invention consists of certain novel combinations, constructions, and arrangements of parts as will be hereinafter fully described and claimed.

In the accompanying drawing:—Figure 1 is a side elevation partly in section of the improved device showing the same in a set-up position and ready to sharpen a pair of shears. Fig. 2 is an end elevation of the assembled device showing the same in a set-up position. Fig. 3 is a detailed perspective view of the foldable guide post. Fig. 4 is a detailed perspective view of one of the jaws of the device. Fig. 5 is a fragmentary side elevation, partly in section, of the connecting portions of the foldable guide post and supporting clamp. Fig. 6 is a section taken

on the line 6—6 of Fig. 1. Fig. 7 is a section taken on the line 7—7 of Fig. 1. Fig. 8 is a section taken on the line 8—8 of Fig. 1, looking in the direction of the arrows. Fig. 9 is a central vertical section taken through the upper portion of the foldable guide post.

Referring to the accompanying drawing by numerals 1 designates the clamp body which is formed so as to constitute a substantially U-shaped clamp which carries at its lower portion 2 the screw 3. This clamp is adapted to be positioned upon a support 4 so as to allow the screw 3 to be threaded into engagement with the support for detachably retaining the clamp in engagement with the support 4. The clamp body 1 has an enlarged portion 5 from which extend the bearing ears 6. These ears 6 are adapted to rest upon the support 4 to more efficiently retain the clamp against shaking or bobbing when in use. The enlarged portion 5 is provided with teeth 7 formed upon its inner surface which are adapted to engage the teeth 8 of the jaw 9 of the vise. A bolt 10 passes through the lower portion of the jaw 9 and the enlarged portion 5 of the clamp body 1 and the wing-nut 11 is threaded into engagement with the bolt 10 so as to hold the teeth 7 and 8 in engagement with each other thereby holding the vise in a set position when in use. This jaw 9 has an integral bifurcated lug 12 extending therefrom to which the reduced end 13 of the jaw 14 is pivotally secured by means of the pivot-screw 15 which passes through the lug 12 and the aperture 16 formed in the reduced end 13 of the jaw 14. By pivotally securing these jaws 9 and 14 together it will be seen that they may be easily separated or swung apart when it is so desired. The upper end 17 of the jaw 9 extends at an oblique angle to the body portion of the jaw 9 while the upper end 18 of the jaw 14 extends at an oblique angle to the jaw 14 so as to extend in the general direction of the upper end 17 of the jaw 9. The outer upper surface of the jaw 14 is beveled as indicated at 19 for purposes hereinafter to be described. In order to hold the jaws against accidental swinging movement when the device is in operation, a bolt 20 is pivotally secured to the jaw 14 by means of the screw 21. This bolt 20 passes through the pocket 22 formed in the jaw 9 and the projection 23 and upon the outer end of this

bolt there is threaded the wing nut 24. As this wing nut is threaded into engagement with the bolt 20 the jaws 9 and 14 will be drawn toward each other and, therefore, 5 when the blade of a pair of shears is positioned between the angularly extending portions 17 and 18 of these jaws, the shears will be held in clamped engagement with the vise. In order to force the jaws apart as soon as the nut 24 has been loosened on the 10 bolt, there is provided a coiled spring 25 which is positioned upon the bolt 20 and rests within the pocket 22. This spring 25 bears at one end against a shoulder 20' 15 formed on the jaw 14 and at the opposite end against the inner end of the projection 23 adjacent the pocket 22. It will be seen that as soon as the spring has forced the jaws 9 and 14 apart the shears which have been clamped in engagement with the vise 20 may be easily removed.

In order to support a stone and a reciprocating rod therefor, there is provided a foldable guide post. This guide post comprises 25 a primary section 26 and an auxiliary section 27 which are pivotally secured together by means of the screw 28. The primary section 26 has an integral wedge-like portion 29 which is adapted to fit in the V-shaped 30 notch 30 of the integral finger 31 of the clamp body 1. This primary section 26 is also provided with the transverse aperture 32 for the reception of the pivot screw 33 which passes through the finger 31 and aperture 35 for pivotally securing the foldable guide post in engagement with the clamp. The auxiliary section 27 is provided with an opening 34 through which the quadrant 35 is adapted to pass. This quadrant has a 40 threaded end 36 which is adapted to engage the primary section 26 of the foldable guide post. The thumb screw 37 is carried by the auxiliary section 27 of the foldable guide post so as to come into binding engagement 45 with the quadrant 35, thereby retaining the auxiliary section 27 at different angles along the quadrant 35. Adjacent the upper end of the auxiliary section 27 there is provided a notched portion 38 which is adapted to 50 carry the plate 39, this plate being held in position by means of the screws 40. The plate 39 and the upper end of the auxiliary section 27 are provided with the beveled portions 41 which form a socket in which the ball 42 is carried. This ball 42 is provided 55 with an opening 43 extending therethrough through which the rod 44 is slidably mounted. This rod 44 is adapted to engage the clamp block 45 by means of the threaded portions 46. A similar rod 47 is threaded 60 into engagement with the clamp block 45 as shown at 48 while the opposite end of the rod 47 passes through the nut 49 positioned within the handle 50. Positioned adjacent this handle upon the rod 47 there is a second-

ary clamping block 51 and each one of these clamping blocks 45 and 51 is provided with depending portions 52 for engaging a stone 53. By the rotation of the handle 50 the nut 49 carried thereby will move along the 70 threaded end 54 of the rod 47. As the handle 50 and nut 49 move along the rod they will push or move the clamping block along the rod 47 and therefore will cause the portions 52 to bind upon the end portions of the stone 53 for detachably retaining the stone in position. As soon as the stone has been clamped the stone may be reciprocated back and forth by means of the handle, since the rod 44 will be allowed to 80 freely reciprocate through the ball 42 without imparting lost motion or binding.

When this device is in use, the foldable guide post is swung so as to allow the auxiliary section 27 to assume a substantially 85 vertical position. The jaws 9 and 14 of the vise may be separated so as to allow the blade of a pair of shears to be positioned therebetween. The wing-nut 24 may then draw the jaws of the vise into engagement 90 with the shears for gripping and holding the same for sharpening. The wing-nut 11 may then be loosened upon the bolt 10 so as to allow the vise to be swung to a desired position as indicated in dotted lines in Fig. 95 1 at which time the nut may be tightened 100 for holding the vise in a set position. If the bevel of the shears does not rest evenly upon the stone 53, then the auxiliary section 27 of the guide post may be swung upon 105 the quadrant 35 to allow the stone to assume the correct angle. The thumb screw 37 may then be tightened so as to hold the guide post in a set position. At this time the stone may be reciprocated by moving the 110 handle 50 back and forth as the rod 44 will freely reciprocate through the ball 42 carried by the auxiliary section 27 and the plate 39. By the passing of this stone 53 over the edge of the blade the blade may be 115 easily and quickly sharpened. By the provision of the ball it will be seen that the stone may be swung from one side to the other so as to engage the edge of the blade of the shears which will project beyond the 120 side portions of the vise as shown in dotted lines in Fig. 2. As soon as the blade has been sharpened the nut 24 may be quickly loosened on the bolt 20 at which time the spring 25 will force the jaws of the vise 125 apart so as to allow the jaws to be opened so that the shears may then be removed. By having the wedge-like portion 29 fitting within the V-shaped pocket 30 of the finger 31 any tendency of lateral movement by the 130 folded guide post will be greatly reduced, thus relieving the strain from the pivot screw 33. When the device is not in use, the vise may be swung and held in a vertical position. The rod 44 may then be removed

from the opening 43 formed in the ball 42. The auxiliary section 27 of the foldable guide post may be swung downwardly so as to rest upon the primary section 26 as shown in dotted lines in Fig. 1. The screw 3 may be removed from engagement with the support 4 at which time the clamp 1 may be lifted from engagement with the support. The primary section 26 of the folded guide post may then be swung upwardly so as to extend in a vertical parallel plane with the vise. The rod 44 may also be removed from engagement with the clamping block 45 so that the entire device will assume a very compact position when not in use.

From the foregoing description it will be seen that a simple and an efficient device has been produced for sharpening shears which may be easily adjusted to accommodate different sized shears so as to hold the shears in a correct position for allowing the shears to reciprocally engage the stone for allowing the same to be sharpened.

It is obvious that many minor details of construction may be changed in the construction of this invention without departing from the spirit of the invention and therefore it is desired to include all such devices as properly come within the scope of the device as claimed.

What I claim is:—

1. In a sharpening device comprising a supporting body, a vise adjustably secured to said body, a foldable guide post pivotally secured to said body, means reciprocally supported by said guide post for supporting a stone, said means being adapted to reciprocate said stone adjacent the outer end of said vise, whereby a blade carried by said vise may be sharpened.

2. In a sharpening device of the class described, the combination with a supporting body, a vise adjustably secured to said body, said vise comprising a pair of jaws, one of said jaws being pivotally secured to the other jaw, means for retaining said jaws in engagement with a blade carried thereby, a foldable guide post secured to said supporting body, a ball carried by said guide post, 50 a rod slidably mounted through said ball,

and means carried by said rod for clamping upon a stone whereby a stone may be reciprocally adjusted adjacent the outer end of said vise, for sharpening a blade carried by said vise.

55

3. In a sharpening device of the class described the combination with a supporting member, a vise adjustably secured to said supporting member, a foldable guide post pivotally secured to said supporting member, a ball carried by said foldable guide post, a rod passing through said ball and adapted to freely reciprocate, a clamping block secured to said rod, a second rod engaging said clamping block, a clamping block slidably mounted upon said last-mentioned rod, a handle threaded into engagement with said last-mentioned rod whereby said last-mentioned clamping block may be moved upon said first-mentioned clamping 70 block for clamping a stone, said rods being adapted to reciprocate, a stone carried by said clamping block adjacent the outer end of said vise whereby a blade carried by said vise may be sharpened.

75

4. In a sharpening device of the class described the combination with a supporting member, a vise adjustably secured to said supporting member, a foldable guide post pivotally secured to said supporting member, said guide post comprising a primary section and an auxiliary section, said primary section being adapted to space said auxiliary section at a spaced distance from said vise, means for retaining said auxiliary section in 85 an adjusted set position, a ball carried by said auxiliary section, said ball provided with a central opening, a slidable clamping means engaging said ball, said slidable clamping means adapted to engage a stone 90 whereby a stone may be reciprocated adjacent the outer end of said vise for sharpening a blade carried thereby.

In testimony whereof I hereunto affix my signature in presence of two witnesses.

WALTER C. B. FARRAR.
